SWITCHBOARD WIRING

Paul S. Graham, Turtle Creek, Pa., assignor to
Westinghouse Electric & Manufacturing Com-
pany, East Pittsburgh, Pa., a corporation of
Pennsylvania

Application March 7, 1940, Serial No. 322,787

5 Claims. (Cl. 174—52)

My invention relates, generally, to switchboard wiring and, more particularly, to the wiring of switchboards having swinging panels or doors.

In the wiring of switchboards having swinging panels or doors it is necessary to provide flexible wire loops for connecting between the wires on the swinging member and those on the fixed member. Heretofore, the wiring cleats for holding the wires in position have been made of two strips, of substantially the same width, between which the wires are clamped. As the swinging member swings out and back on its hinges, the connecting wire loop flexes out to approach a straight line and returns to its loop form. In so doing the wire necessarily bends back and forth at the cleats. With cleats of substantially the same width the wire bends back and forth at the same point over a relatively wide angle. If the swinging member is operated frequently there is danger of the wire breaking at the point of bending.

An object of my invention, generally stated, is to provide an improved wiring cleat for holding flexible wires which are subjected to bending.

A more specific object of my invention is to decrease the likelihood of breakage of flexible wires which interconnect relatively movable members.

Other objects of my invention will be explained fully hereinafter or will be apparent to those skilled in the art.

According to my invention, the cleating device for holding the flexible wires in position comprises two strips of unequal widths between which the wires are clamped to form flexible loops. With strips of different widths, each wire bends back and forth at two points alternately, thereby decreasing the angle of bending and the likelihood of breakage of the wire.

For a fuller understanding of the nature and objects of my invention, reference may be had to the following detailed description, taken in conjunction with the accompanying drawing, in which:

Figure 1 is a view, partially in plan and partially in section, of a portion of a switchboard structure embodying my invention and showing a swinging panel in the closed position;

Fig. 2 is a view, in elevation, of the structure shown in Fig. 1;

Fig. 3 is a view, similar to Fig. 1, showing the swinging panel in the open position; and

Fig. 4 is a view, in plan, of a pair of wire cleats constructed according to the prior art and showing the bending action on the wire.

Referring to the drawing, and particularly to Fig. 1, the switchboard structure shown therein comprises portions of a stationary panel 10 and a swinging panel 11 which swings on a hinge 12. The panels 10 and 11 may be composed of steel or other suitable material for enclosing and supporting switchboard apparatus.

In order to make connections from a terminal block 13 on the panel 10 to apparatus mounted on the swinging panel, it is necessary to provide flexible conductors 14 for interconnecting between the stationary panel 10 and the swinging panel 11. As shown in Fig. 1, each wire 14 forms a loop 15 when the swinging panel 11 is in the closed position and, as shown in Fig. 3, the loop 15 is opened out when the swinging panel is in the open position.

In accordance with the usual practice, the wires 14 are held in position on the panels by wiring cleats 16 between which the wires are disposed. One of the wiring cleats 16 is mounted on the swinging panel 11 by a bracket 17 and the other cleat is mounted on the fixed panel 10 by a bracket 18. The loop 15 is formed between the cleats 16.

In order to decrease the likelihood of breakage of the wires 14 when the panel 11 is swung back and forth, each one of the cleats 16 is composed of a pair of strips 21 and 22 which are of unequal widths instead of the same width, as is the usual practice. As shown, the strip 21 is substantially wider than the strip 22, the strip 21 being approximately twice the width of the strip 22. The strips 21 and 22 are drawn together by bolts 23 to clamp the wires 14 firmly.

As shown in Fig. 1, the wire 14 is bent at the points 24 and 25 when the swinging panel 11 is closed. As shown in Fig. 3, the bending takes place at the points 26 and 27 when the panel 11 is open. Thus, the wire has straightened at the points 24 and 25 and the bending transferred to the points 26 and 27 as the panel 11 is opened. When the panel 11 is again closed, the wire straightens at the points 26 and 27 and bends at 24 and 25. In this manner the wire bends at the different points alternately and not at the same point all the time as is the case when the strips of the wiring cleat are the same width, as shown in Fig. 4.

Furthermore, the angle of bending at any one point is materially reduced, as will be seen by comparing Fig. 4 with Figs. 1 and 3. Therefore, the likelihood of breakage of the wire by the bending action is decreased by utilizing the

wiring cleats having strips of unequal widths, as herein described.

While I have illustrated the improved wiring cleats as applied to switchboard panels, it will be understood that wiring cleats constructed according to my invention may be utilized with apparatus of other types, as well as in switchboard structures. Also, the strips of unequal width which form the cleat may be reversed from the positions shown in the drawing, that is, the narrow and wide strips may be interchanged, if desirable, because of space limitations.

Since numerous changes may be made in the abovedescribed construction, and different embodiment of the invention may be made without departing from the spirit and scope thereof, it is intended that all matter contained in the foregoing description or shown in the accompanying drawing shall be interpreted as illustrative and not in a limiting sense.

I claim as my invention:

1. In a switchboard structure, in combination, a stationary member, a swinging member, a flexible wire interconnecting said members, and oppositely disposed wiring cleats for holding said wire in position, each wiring cleat comprising a pair of strips disposed in spaced relation, the adjacent edges of said wiring cleats being stepped to cause the wire to bend at different points alternately, thereby reducing the angle of bending of the wire as the swinging member is moved back and forth.

2. In a switchboard structure, in combination, a stationary panel, a hinged swinging panel, a flexible conductor interconnecting said panels, 35

and oppositely disposed wiring cleats for holding said conductor in position, each wiring cleat comprising a pair of strips between which the conductor is disposed, one of said strips being substantially wider than the other and having one edge offset from the other, the other edges being in alignment, and means for drawing said strips together to hold the conductor.

3. In a switchboard structure, in combination, 10 a stationary panel, a hinged swinging panel, a flexible conductor enterconnecting said panels, and wiring cleats for holding said conductor in position, each wiring cleat comprising a pair of strips between which the conductor is disposed, one of said strips being approximately twice the width of the other, and means for drawing said strips together to hold the conductor.

4. The combination with a stationary member, 15 a hinged member and a flexible conductor interconnecting said members, of means for reducing the angle of bending of the conductor where it is connected to said members, said means comprising a pair of strips for securing the conductor to each member, said strips having their adjacent edges offset.

5. The combination with a stationary member, 20 a hinged member and a flexible conductor interconnecting said members, of means for reducing the angle of bending of the conductor where it is connected to said members, said means comprising a pair of strips for securing the conductor to each member, said strips having their adjacent edges offset by an amount equal to or greater than the width of the conductor.

PAUL S. GRAHAM.
